US0D1108992S

(12) **United States Design Patent** (10) Patent No.: **US D1,108,992 S**
(45) Date of Patent: ** Jan. 13, 2026

(54) **SENSOR SUPPORT**

(71) Applicant: **TAUA S.R.L.**, Bologna (IT)

(72) Inventor: **Andrea Romagnoli**, Bologna (IT)

(73) Assignee: **TAUA S.R.L.** (IT)

(**) Term: **15 Years**

(21) Appl. No.: **29/859,273**

(22) Filed: **Nov. 9, 2022**

Related U.S. Application Data

(62) Division of application No. 35/512,134, filed on Jan. 7, 2021 (U.S. filing date under 35 U.S.C. 384), and
